[57] CLAIM

The ornamental design for a metalwood golf club head, as shown and described.

DESCRIPTION

FIG. 1 is a front perspective view of a metalwood golf club head according to the invention showing the hosel, shaft and grip in dotted line;

FIG. 2 is an enlarged front perspective view of the metalwood golf club head shown in FIG. 1;

FIG. 3 is a rear perspective view of the metalwood golf club head shown in FIG. 1;

FIG. 4 is a front elevation view of the metalwood golf club head shown in FIG. 1;

FIG. 5 is a rear elevation view of the metalwood golf club head shown in FIG. 1;

FIG. 6 is a top plan view of the metalwood golf club head shown in FIG. 1;

FIG. 7 is a bottom view of the metalwood golf club head shown in FIG. 1;

FIG. 8 is an end view of the metalwood golf club head shown in FIG. 1 taken from the toe end; and,

FIG. 9 is an end view of the metalwood golf club head shown in FIG. 1 taken from the heel end.

The broken line showing is for illustrative purposes only and forms no part of the claimed design.
